UNITED STATES PATENT OFFICE.

GEORGE B. CARTER AND WILLIAM L. BERTRAM, OF DETROIT, MICHIGAN, ASSIGNORS
TO GREAT WESTERN STOVE COMPANY, OF LEAVENWORTH, KANSAS, A CORPORA-
TION OF KANSAS.

DESIGN FOR A STOVE.

43,563.

Specification for Design.

Patented Feb. 18, 1913.

Application filed November 6, 1912. Serial No. 729,911. Term of patent 14 years.

To all whom it may concern:

Be it known that we, GEORGE B. CARTER and WILLIAM L. BERTRAM, citizens of the United States of America, residing at Detroit, in the county of Wayne and State of Michigan, have invented a certain new, original, and ornamental Design for Stoves, of which the following is a specification, reference being had therein to the accompanying drawings, forming part thereof.

The figure is a perspective view of a stove embodying our new design.

We claim:

The ornamental design for a stove, as shown.

GEORGE B. CARTER.
WILLIAM L. BERTRAM.
